UNITED STATES PATENT OFFICE.

FRANK B. DAVIDSON, OF MARSEILLES, ILLINOIS, ASSIGNOR TO HOWE AND DAVIDSON COMPANY, OF EAST ORANGE, NEW JERSEY, A CORPORATION OF NEW JERSEY.

CONTAINER.

No. 889,109.

Specification of Letters Patent.

Patented May 26, 1908.

Application filed April 20, 1907. Serial No. 369,331.

To all whom it may concern:

Be it known that I, FRANK B. DAVIDSON, a citizen of the United States, and a resident of Marseilles, in the county of Lasalle and 5 State of Illinois, have invented certain new and useful Improvements in Containers; and I do hereby declare that the following is a full, clear, and exact description thereof, reference being had to the accompanying 0 drawings, and to the letters of reference marked thereon, which form a part of this specification.

This invention relates to a novel paper box or container made from a single sheet of stiff or heavy paper-board, straw-board or like sheet material and designed more especially to be used in the place of a wooden packing box for containing a number of packages, filled cartons or the like.

10 The invention consists in the matters hereinafter set forth and more particularly pointed out in the appended claims.

In the accompanying drawings:—Figure 1 illustrates in perspective the set-up box. Fig. 2 is a plan view of the blank from which my improved box is made. Fig. 3 is a perspective view of the top portion of the box showing the manner of closing the top thereof. Fig. 4 is a vertical section on the line 4—4 of Fig. 6. Fig. 5 is a vertical section on the line 5—5 of Fig. 4. Fig. 6 is a plan view of the top of the box with parts broken away. Fig. 7 is a perspective view of a box of different dimensions, showing a slightly different manner of closing the top thereof. Fig. 8 is a vertical longitudinal section through the top portion of said box shown in Fig. 7. Fig. 9 is a vertical section on line 9—9 of Fig. 8. Fig. 10 is a plan view of a blank of slightly modified form. Fig. 11 is a plan view of the top of a box made from said blank shown in Fig. 10. Fig. 12 is a fragmentary plan view showing a modified form of the interlocking notch and tongue on the opposite flaps of the box.

Said container is made from an elongated, single piece blank, shown in Fig. 2, which is bent into tubular form along the transverse score-lines a a^1 a^2 a^3 and provided at one of its ends with a short flap or extension a^4 which is secured to the end margin of the opposite end of the blank by paste or other means. The four sections of the blank formed by said score-lines constitute the side walls A A^1 A^2 A^3 of the box and said sections

are provided at their end margins with flaps A⁴ A⁵ A⁶ A⁷, separated from the said sections by score-lines a⁵ a⁶ a⁷ a⁸ and from each other by slits perpendicular to the said score-lines.

In forming the container from the blank described the blank is bent along the score-lines into tubular form and the end flap A^4 secured to the opposite end of the blank. The marginal flaps $A^4 A^5 A^6 A^7$ at both sides of the blank are bent or turned inwardly with their ends overlapping each other, as clearly shown in Fig. 3. These inturned end or top and bottom flaps form the top and bottom walls of the box. In Figs. 3 to 6, inclusive, is shown the manner of forming the top wall or cover of the box, it being understood that the opposite or bottom wall is formed in an identical manner. As shown in Fig. 3 the flaps A^5 and A^7 on the top margins of opposite side walls A^1 and A^3 are first folded inward or toward each other and thereafter the flaps A^4 and A^6 are folded toward each other over the flaps A^5 and A^7 . As shown in Figs. 1 to 6, each of the two flaps A^5 and A^7 extends less than half of the distance across the top of the box, leaving an opening between the inner or adjacent end margins of said flaps A^5 and A^7 which is closed by the two flaps A^4 and A^6 . The two flaps A^4 and A^6 meet at their inner margins a^9 and a^{10} , respectively, and are adapted for interlocking engagement edge to edge with each other. As shown in said Figs. 1 to 6, the flaps A^4 and A^6 are provided at their meeting edges, one with a tongue and the other with a notch, and said tongue and notch are made generally of dove-tail shape so that when they are engaged with each other in edge to edge relation, an interlocking connection will be formed adapted to prevent the separation of said flaps from each other. In the particular construction illustrated in said Figs. 1 to 6, the flap A^4 is provided on its margin with a tongue a^{11} which is formed by removing a portion of the mate-

is formed by removing a portion of the material at the corners of said flap along lines a^{12} 100 parallel with the margin a^9 and along curved lines a^{13} a^{13} extending from the inner ends of said lines a^{12} through the margin a^9 , and the flap A^6 is provided on its inner margin a^{10} with a notch a^{14} and formed by cutting 105 through the margin a^{10} into said flap along curved lines a^{15} a^{15} of the same shape as the curved lines a^{13} a^{13} , and along a line a^{16} parallel to the line a^{10} and of a length equal to the length of the margin a^9 of the flap A^3 . 110

In Figs. 3 to 6, inclusive, B indicates a rectangular piece of sheet material, such as heavy paper or the like, which covers the space or gap between the edges or margins of the infolded flaps A⁵ and A⁷ and is interposed between the adjacent surfaces of the external flaps A⁴ and A⁶ and the inner flaps A⁵ and A⁷. Said sheet B overlaps and is pasted or otherwise secured to the inner or adjacent margins of the flaps A⁵ and A⁷ and is likewise pasted or otherwise secured to the inner surfaces of the flaps A⁴ and A⁶. Said sheet extends across the top of the box the full distance between the outer margins of the flaps A⁴ and A⁶ but does not extend the full distance between the outer margins of the flaps A⁵ and A⁷, or said sheet B may meet the top margins of the walls A and A² but may not reach to the walls A¹ and A³. As shown in said Figs. 3 to 6, inclusive, the top wall or cover of the box is formed by first folding down the flaps A⁵ and A⁷ and securing the end portions of the sheet B to said flaps A⁵ and A⁷ by paste, glue or other adhesive substance. The flaps A⁴ and A⁶ are then folded down upon and secured by paste, glue or other adhesive substance to said sheet B and to the outer surfaces of the flaps A⁵ and A⁷ where the latter are not covered by said sheet B, the tongue a¹¹ being brought into engagement with the notch a¹⁴. When the said flaps A⁴ and A⁶, which constitute the outer flaps, are brought together into the same plane with each other, and meet at their margins edge to edge, the interlocking of the tongue and notch on the meeting edges of said outer flaps, in the manner described, serves to hold said flaps from spreading apart or separating temporarily or until the paste or glue dries or hardens sufficiently to firmly hold the flaps in their folded positions, and such interlocking also serves to strengthen the end wall by resisting any tendency of the outer flaps spreading apart under internal pressure exerted outwardly on the side walls to which said outer flaps are attached in the subsequent handling of the box. The interlocking of said tongue and notch also insures the box being brought accurately into rectangular form at the time of setting up or closing the box, because the tongue cannot be brought into engagement with the notch unless the side walls are at right angles to each other. Such interlocking also serves, in the finished box, to aid the paste or glue in holding the box in rectangular form, or from distortion by pressure coming on opposite corner edges thereof.

The adhesive substance used for securing the outer flaps to the other parts constituting the end wall may be applied between the entire inner surfaces of said outer flaps and the surfaces of the sheet B and flaps A⁵ and A⁷, or to a part only of said surfaces, the effect in any case being that the said outer flaps are

secured to the inner flaps A⁵ and A⁷, and said outer flaps are held in the same plane with each other, with the tongue and notch thereof in interlocking engagement. If the sheet B be omitted, the said outer flaps will be secured by the paste or glue directly to the inner flaps A⁵ and A⁷, but when said sheet B is used the same result will be obtained, because the said sheet will be secured in whole or in part at both sides thereof to the inner and outer flaps between which it is interposed. The bottom wall of the box is formed in a manner in all respects identical with the manner of forming the top wall or cover.

In Fig. 7 is shown a box of such dimensions that the flaps A⁴ and A⁶ thereof meet along a line considerably longer than the meeting line of the flaps A⁴ and A⁶ of the box shown in Figs. 1 to 6, inclusive. In Figs. 8 and 9 is shown the manner of forming the top wall or cover of said box shown in Fig. 7. As shown in said Figs. 7, 8 and 9, the box is constructed in the same manner as the box shown in Fig. 1 except that the sheet B is replaced by a rectangular sheet C of heavy paper-board, straw-board or like material of the same length and breadth as the box. Said sheet C is interposed between the adjacent surfaces of the inner flaps A⁵ and A⁷ and outer flaps A⁴ and A⁶, as above described, and said sheet extends across the top of the box the full distance between the outer margins of the flaps A⁵ and A⁷ and A⁴ and A⁶ and is secured by adhesive substance to the said inner and outer flaps.

In Figs. 10 and 11 is shown a form of construction in which the flaps A⁴ and A⁶ are engaged or interlocked at their adjacent margins in a manner different from that shown in Figs. 1 to 9, inclusive. As shown in said Figs. 10 and 11, each of the flaps A⁴ is provided at its inner margin a⁹ with a rectangular tongue formed by cutting the side margins of said flaps along lines a¹⁷ a¹⁷ parallel with the margins a⁹ and thence along lines perpendicular thereto, extending through said margin a⁹. Each of the flaps A⁶ is provided at its inner margin a¹⁰ with a rectangular notch formed by cutting through said margin along lines a¹⁸ a¹⁸ perpendicular thereto and thence along a line a¹⁹ parallel to said margin. The box shown in Figs. 10 and 11 is closed by the use of an adhesive substance in the manner hereinbefore described, a sheet B being usually interposed between the adjacent surfaces of the flaps A⁵ and A⁷ and A⁴ and A⁶ as above described.

In the construction shown in Figs. 10 and 11, the tongue and notch on the meeting edges of the outer flaps, while they do not interlock in a manner to hold the said flaps from spreading apart, serve the important purpose of insuring that the box body will be brought accurately into rectangular form when the flaps are folded together in the act

of forming the end wall or walls, because the tongue cannot be inserted in the notch in a manner to bring the side edges of the tongue into edge to edge engagement with the sides 5 of the notch, unless the side walls of the box be at right angles to each other. Moreover, the interlocking of such tongue with the notch, in this form of the same, strengthens the box in a manner to resist a force applied 10 at one of its opposite vertical corner edges, in a manner tending to distort or collapse the box. It is evident that in collapsing the box by a force so applied, the meeting margins of the flaps A⁴ and A⁶ must shift or move end- 15 wise relatively to each other. The engagement of the said tongue with the notch of the associated flap manifestly acts to resist such relative movement of the outer flaps, and thereby tends to strengthen the box.

20 In Fig. 12 I have shown the opposite flaps A⁴ and A⁶ as provided with a tongue and notch which are made of dove-tail form, their lateral margins being straight and inclined, instead of curved, as illustrated in Figs. 1 to 25 7. The tongue and notch, when shaped as shown in said Fig. 12, afford the same general result that is obtained by the construction shown in Figs. 1 to 7. The interlocking of said tongue and notch acting to hold the 30 flaps from relative movement in the direction of the meeting edges thereof, and also preventing separation of the flaps by a movement away from each other to the extent required to hold the flaps together until the 35 paste or glue used to close the end of the box has dried or hardened sufficiently to firmly secure the flaps in place.

A container made in accordance with my 40 invention is constructed of relatively stiff or stronger paper or straw-board and adapted for use in place of wooden packing boxes or cases for containing packages of light materials, such as cereals and the like. The 45 end walls of the box, made as described, afford a box of great strength in proportion to the amount of sheet material used in its construction, and the box, as a whole, may be cheaply made and set up for use by unskilled labor.

50 In making up a package by the use of the container described, the flaps A⁴ A⁵ A⁶ A⁷ at one end of the body will first be folded inwardly and the end wall completed in the manner described. When one end wall has 55 thus been formed the box will be turned to bring the completed wall downward and in contact with the floor or other flat supporting surface. The packages constituting the contents of the container will then be inserted 60 therein and the weight thereof, coming on the closed end wall, will hold the flaps constituting the latter in close contact with each other and under pressure until the paste or glue used for securing them together shall 65 have dried or hardened sufficiently to pre-

vent separation of said flaps under the weight of the contents of the box. After the packages have been inserted the upper end flaps will be folded inwardly over the packages within the container and secured in the manner above described. 70

The container described has the advantage that it can be transported in a flat or knock-down form. In practice, the container body is made into a tubular form by pasting the end flap a⁴ to the opposite end margin of the blank and it may thereafter be folded flat along the score-lines at opposite edges of the box or container. The marginal flaps constituting the flanges are, in this instance, unfolded or in the same plane with the walls of the body or sections to which they are attached. While I have shown in the accompanying drawings the outer flaps A⁴ and A⁶ as provided with a tongue and notch adapted 75 for engagement with each other when the said flaps are brought into the same plane or into edge to edge relation, yet it is to be understood that this feature may be applied as a means of joining opposite flaps arranged to 80 meet each other as stated when the box is constructed, in other respects, in a manner different from that illustrated and hereinbefore described. 85

While I prefer to employ an adhesive substance for securing or holding in their folded positions the interlocking flaps in the manner set forth, yet many of the advantages arising from my invention may be obtained in a box in which the said flaps are so held or secured 90 in position by other fastening or securing means, and it is therefore to be understood that my invention covers or includes a box in which the interlocked flaps are secured to a flat piece or pieces beneath them, or are 95 otherwise secured in their folded or interlocked position, either by an adhesive substance or other securing means. 100

I claim as my invention:

1. A box of sheet material having on opposite side walls thereof flaps adapted to be folded inwardly and to meet each other edge to edge when brought into the same plane with each other, said flaps being provided one with a notch and the other with a tongue; 110 said tongue being adapted to enter and fit within the notch with the margins of the tongue and notch in edge-to-edge relation. 115

2. A box of sheet material having on opposite side walls thereof flaps adapted to be 120 folded inwardly and to meet each other edge to edge when brought into the same plane with each other, said flaps being provided one with a notch and the other with a tongue; said notch and tongue being adapted for interlocking engagement in a manner to prevent separation of the flaps from each other, and the tongue being adapted to fit within the notch with the margins of the tongue and notch in edge-to-edge relation. 125 130

3. A box of sheet material having on opposite side walls thereof flaps adapted to be folded inwardly and to meet each other edge to edge when brought into the same plane
5 with each other, said flaps being provided one with a notch and the other with a tongue, said tongue being adapted to enter the notch and to fit within the same with the margins of the tongue and notch in edge to edge relation, and a flap member of sheet material applied beneath said flaps and to which the latter are secured by adhesive material.
10 4. A box of sheet material having connected side walls and an end wall, said end
15 wall embracing flaps on opposite side walls which are folded inwardly into the same plane and meet each other edge to edge, said flaps being provided one with a notch and

the other with a tongue and the said tongue being adapted to enter said notch and to fit 20 within the same with the margins of the notch and tongue in edge-to-edge relation, and other flaps on intermediate side walls which are folded inwardly into the same plane with each other beneath the first mentioned flaps and to which the latter are secured by adhesive material. 25

In testimony, that I claim the foregoing as my invention I affix my signature in the presence of two witnesses, this 13th day of April A. D. 1907. 30

FRANK B. DAVIDSON.
